ABSTRACT OF THE DISCLOSURE

An energy-storing and release mechanism, usable to actuate bomb shackle release devices and the like, which comprises a housing defining an elongated chamber, a plunger mounted within the chamber and longitudinally movable therein from an energy storing cocked position to a released position, energy-storing means operable to move the plunger from the cocked to the released position, locking means engageable with the plunger to releasably retain the plunger in the cocked position and further having an unlocked position disengaged from the plunger permitting the energy-storing means to move the plunger toward the released position, and planetary cam means operably engageable with said locking means and moveable from a first position in engagement with said locking means to releaseably retain said locking means in said locked position and further movable to a second position permitting said locking means to move to said unlocked position.

This invention relates generally to an electro-mechanical energy storing and release mechanism, and more particularly relates to an improved actuator mechanism of the type disclosed in United States Patent 2,776,570 for controlling a bomb shackle release device.

General disclosure

It is well known that the actuator mechanisms for controlling aircraft bomb release devices, as described and claimed in the above-mentioned patent, must meet rigid design and operating standards before being adopted for use under adverse field conditions. Because of the necessarily limited supply of electrical power on most military aircraft, such bomb actuator mechanisms must be designed to impart a substantial releasing force to the bomb shackle release levers when energized by a relatively small amount of electrical energy. Adverse field conditions further require the type of actuator mechanisms under consideration to be very compact and light weight, easily and economically assembled and repaired, and capable of withstanding severe temperature, shock and vibration conditions.

The electro-mechanical actuator described and claimed in the aforementioned Patent 2,776,570 has been very successful in meeting the above-mentioned structural and operational requirements for bomb release actuators. As illustrated in said patent, which is assigned to the assignee of the present application, the type of bomb release actuator under consideration comprises a spring-loaded plunger assembly which is releasably locked in a cocked energy storing position by cam-operated locking and release means. In addition, the cam means which operates the locking and release means is connected to a solenoid assembly or the like which upon energization moves the

2

cam and releases the locking and release means from the plunger, thereby permitting the spring to forcefully drive the plunger assembly against the release lever of an aircraft bomb shackle.

5 This invention contemplates providing such bomb release actuators with an improved locking and release means and a novel planetary cam assembly which cooperate to releasably retain the plunger assembly in the aforementioned cocked energy storing position. It has been found that the addition to such actuators of the improvements in accordance with this invention substantially enhances the structural and operational characteristics of the actuator, and particularly decreases the amount of electrical energy needed to operate the mechanism. In addition, the improvements in accordance with this invention substantially reduce the costs of manufacturing the actuator by providing a mechanism which can be readily machined with a minimum of critical tolerances and which can be finally adjusted for maximum 20 performance during assembly.

It is therefore an object of this invention to provide an improved electro-mechanical actuator mechanism suitable for use with an aircraft bomb shackle release device.

25 It is a further object of this invention to provide an improved electro-mechanical actuator which may be readily energized by a small amount of electrical energy to impart a substantial releasing force to an aircraft bomb shackle release lever.

30 It is a still further object of this invention to provide an improved actuator mechanism that is compact and lightweight, and which can withstand severe temperature, shock, and vibration conditions.

Disclosure of a specific embodiment

Another object of this invention is to provide an improved electro-mechanical actuator mechanism which may be economically manufactured with a minimum of critical machine tolerances, and which may be accurately adjusted for maximum performance at the time of assembly.

More specific objects and features of this invention will become apparent from a description of an embodiment thereof, as illustrated in the accompanying drawings. In these drawings:

40 FIGURE 1 is an end view of the assembled actuator mechanism in accordance with this invention;

45 FIGURE 2 is an enlarged cross-sectional view of the actuator taken along the line 2—2 in FIGURE 1 showing the actuator in the cocked energy-storing position;

50 FIGURE 3 is a cross-sectional view taken along the line 3—3 in FIGURE 2;

55 FIGURE 4 is a fragmentary cross-sectional view taken along the line 4—4 in FIGURE 2;

FIGURE 5 is a fragmentary cross-sectional view taken along the line 5—5 in FIGURE 2;

60 FIGURE 6 is a fragmentary cross-sectional view taken along the line 6—6 in FIGURE 2;

FIGURE 7 is a fragmentary cross-sectional view taken along the line 7—7 in FIGURE 2;

FIGURE 8 is a further enlarged fragmentary cross-sectional view taken along the line 8—8 in FIGURE 2;

65 FIGURE 9 is a further enlarged fragmentary sectional view of the plunger end of the actuator assembly shown in a cocked energy storing position;

FIGURE 10 is an enlarged and exploded perspective view of the internal portion of the actuator assembly showing the locking and planetary cam release mechanism in accordance with this invention;

FIGURE 11 is a rearward perspective view of the spider portion of the planetary cam release mechanism shown in FIGURE 10;

FIGURE 12 is an enlarged fragmentary sectional view of the actuator as shown in FIGURE 2 illustrated in fired or released position;

FIGURE 13 is a fragmentary cross-sectional view taken along the line 13—13 in FIGURE 12;

FIGURE 14 is a further enlarged fragmentary sectional view taken along the line 14—14 in FIGURE 12;

FIGURE 15 is a further enlarged fragmentary cross-sectional view taken along the line 15—15 in FIGURE 12; and

FIGURE 16 is a further enlarged fragmentary sectional view of the actuator as shown in FIGURE 9, illustrated in the fired or released position.

Referring generally to FIGURE 2, the actuator mechanism in accordance with this invention comprises a body or housing 10 which defines a substantially cylindrical chamber 11. This housing 10 includes a support bracket 12 having bolt holes 13 for securing the assembled actuator in the proper position on a bomb release shackle (not shown). Housing 10 is further provided with a plug 14 and washer 15 which maintain the actuator components, described hereinafter, in proper assembled position within the housing 10, and which seal one end of chamber 11 so that the assembly is not subjected to the moisture and dirt, or severe temperature variations of the surrounding atmosphere. The housing 10, plug 14 and washer 15 are preferably made from a metal having a high magnetic reluctance.

This actuator mechanism also includes an electro-magnetic solenoid unit 20 housed at one end of the chamber 11 and a spring-loaded plunger assembly 50 housed at the other end of the chamber. In accordance with this invention, this solenoid unit 20 when energized operates through novel locking and release means 80 and planetary cam assembly 100 to release this spring-loaded plunger assembly 50 and allow the plunger to forcefully impact a bomb shackle release lever.

Referring to FIGURE 2 more specifically, the solenoid unit 20 includes a stator 21 having a central core portion 21' surrounded by the wire energizing coil 23 that is wound about a coil spool 24. The left end of this stator core 21' in this embodiment, as viewed in FIGURE 2, extends outwardly beyond spool 24 and forms a tubular element 22 to receive the plunger assembly 50, as further described hereinafter, and the outer or peripheral portion of stator 21 provides four spaced pole pieces 27, 28, 29 and 30 (FIGURE 3) which extend beyond spool 24 to the right in FIGURE 2. The stator 21 is restrained from rotating within the housing 10 by the set screw 19, and the coil 23 can be connected to a suitable power source (not shown) by lead wires 25 that extend outwardly from the housing through a water-tight fitting 26.

This solenoid unit also includes a rotor 35 secured to a shaft 36. This rotor 35 defines four equally-spaced poles 37, 38, 39 and 40, as seen in FIGURES 3, 10 and 13, which are disposed adjacent the above-described pole pieces 27, 28, 29 and 30 respectively of the solenoid stator 21. By this arrangement, when the coil 23 of this solenoid 20 is energized, these poles on the rotor 35 are attracted toward the respective adjacent poles on the stator 21, as described in said above-mentioned patent, and impart a counter-clockwise rotation to the shaft 36, as indicated by the arrow in FIGURE 3.

This rotor shaft 36, as shown in FIGURE 2, extends through stator 21 and tubular portion 22 along substantially the entire length of housing chamber 11, and is supported for rotation in the stator by sleeve bearings 41 and 42. In addition, a stop-nut 43 and a thrust ball bearing

44 operate to maintain the shaft 36 in the proper lateral position within the actuator housing 10. This thrust bearing 44 also aids in materially reducing the amount of electrical energy needed to actuate the mechanism in accordance with this invention by substantially reducing the drag on the rotor 35 created by the lateral pull of the solenoid 20 on the rotor when the coil 23 is energized.

Referring to FIGURES 4 and 10 the rotor 35 is also provided with a stop pin 45 which extends inwardly from the rotor toward the stator 21 and which travels within an arcuate groove 46 provided in the adjacent face of the coil spool 24. The upper limit of the groove 46 thereby provides an abutment shoulder 47 engageable with the pin 45 to define the extreme clockwise or cocked position of the rotor. A torsion spring 34, shown clearly in FIGURES 3 and 13, is also included in the solenoid unit to urge the rotor 35 clockwise toward this cocked position, and to retain the pin 45 in engagement with the shoulder 47 when the solenoid 20 is not energized. FIGURES 4 and 13 further illustrate that this solenoid unit 20 includes a stop ring 48, formed from soft flux-permeable steel or the like, which is secured to the stator 21 by a suitable retaining clip 49. This stop ring 48 is provided with a tab 48' projecting into the path of counter-clockwise travel of pin 45 on the rotor. The tab 48' is thus engageable with pin 45 to define the extreme counter-clockwise uncocked or released position of the rotor 35, as illustrated in FIGURE 13.

Since this arrangement in accordance with this invention places the stop tab 48' and the stop pin 45 in the magnetic circuit of the solenoid unit 20, the energization of the coil 23 will magnetize the tab and pin, and create a mutual magnetic attraction which draws the pin toward the tab. In addition to providing a stop for the rotor 35, the tab 48' and pin 45 therefore provide a supplementary magnetic torque force as the pin approaches the tab which assists the rotation of rotor 35 through the final angular degrees where the torque force would otherwise be weakened by the closing of the gaps between the rotor 35 and stator poles of the solenoid assembly.

To describe the bomb release-lever engaging portion of this actuator in more detail, the plunger assembly 50 comprises a hollow cylindrical member 55 which is slidably extended over the tubular portion 22 of the stator core 21' and over the shaft 36 within housing chamber 11. A striking cap 56, which will engage the release-lever of the bomb shackle release device during operation of the actuator, is threaded to the outer end of member 55 (FIGURES 2 and 12) and a hollow cylindrical skirt 57 is threaded to the periphery of member 55. The member 55, cap 56 and skirt 57 will thereby move longitudinally outward from within chamber 11 as a complete unit, from the position shown in FIGURE 2 to the position shown in FIGURE 12, when the actuator in accordance with this invention is operated to release the bombs from the aircraft.

To limit the outward travel of this plunger assembly 50, the housing 10 as shown in FIGURES 2 and 12 includes an inward circular flange 10' which surrounds the periphery of the skirt 57. A nylon channel-shaped liner 58, held in place against the skirt 57 by a suitable resilient O ring 59 is also provided within the housing 10, to insure that the sliding junction between skirt 57 and the flange 10' is sealed from the atmosphere surrounding the actuator. A split shock ring 60, having beveled edges 61 is positioned adjacent this O ring 59, and is engageable with an angular flange 63 on the skirt 57 to limit the outward travel of plunger assembly 50. FIGURE 12 shows that the engagement between this flange 63 and the shock ring 60 will force the ring 60 outwardly to the left against the resilient O ring 59 while simultaneously forcing the ring 60 to radially expand into frictional engagement with the housing 10. By this arrangement, the outward lateral movement of the plunger assembly 50 is arrested in a manner which cushions the impact between

the skirt 57 and the housing 10 so that shock and vibration forces resulting from the operation of the actuator mechanism are minimized.

As discussed in the aforementioned Patent 2,776,570, the energy storing means used in the type of actuators under consideration comprises a strong compression spring 70 which is substantially fully compressed when the actuator is locked in a cocked position, as illustrated in FIGURES 2 and 9, and which operates when unlocked to bring the plunger assembly 50 into engagement with the release-lever of the bomb shackle device with a substantial impact force. In this embodiment, the energy storing compression spring 70, having a compressive force of approximately 30 pounds is mounted around the tubular portion 22 between the stator 21 and the plunger assembly 50, and is operative upon release of the plunger assembly 50 to rapidly force the plunger outwardly until the motion is arrested by the engagement of flange 63 with the shock ring 60, as described hereinabove. A key 75 secured to the tubular portion 22 of the stator 21 is in engagement with a longitudinal keyway 76 provided in the interior surface of hollow member 55, and guides the outward movement of plunger assembly 50 during the bomb-releasing operation.

The bomb release actuator mechanism in accordance with this invention further includes an improved locking and release latch 80, as seen in FIGURES 9 and 10, to releasably retain the plunger assembly 50 in a cocked energy storing position. Latch 80 is pivotally mounted adjacent the plunger assembly 50 on pins 81 within a longitudinal groove 79 in the tubular portion 22 of the stator core. The latch 80 further includes a detent 82 which is engageable with an interior surface 83 of the plunger assembly 50. As shown in FIGURES 2 and 9, when this latch 80 is pivoted about pins 81 to a locked position, the detent surface 82 engages with the interior surface 83. The plunger assembly 50 is thereby retained in a cocked position within the housing 10 and the energy of the compressed spring 70 is stored.

FIGURES 12 and 16 illustrate that this locking latch 80 in accordance with this invention also pivots about the pins 81 into an unlocked position to disengage the detent 82 from the interior surface 83 of the plunger assembly and thereby release the stored energy of the compressed spring 70. When the latch 80 is moved from the locked to the unlocked position, it is apparent that spring 70 will then forcefully drive the plunger assembly 50 outwardly against the release-lever of the bomb shackle. To insure that the plunger assembly 50 is rapidly released, the latch 80 in this illustrated embodiment is pivoted within the actuator housing 10 so that the compression spring 70 urges the latch toward this unlocked position. As seen in FIGURE 9, the pivot pins 81 of the latch are thus secured to the actuator assembly in a position spaced from the detent 82 so that a moment arm is defined between the pins and the detent. The lateral releasing force of the compressed spring 70, applied to the latch 80 through the detent 82, thereby creates a moment force which tends to rotate the latch to the above-described unlocked position. By this arrangement, the need for additional means to produce a quick release of the latch 80 is eliminated.

The bomb release mechanism in accordance with this invention further includes an improved planetary cam assembly 100 which is mounted on rotor shaft 36, and which cooperates with the latch 80 to releasably retain the latch in a locked position against the biasing force of spring 70. As illustrated in FIGURE 10, the planetary cam assembly 100 comprises a cam sleeve 101 defining an arcuate cam surface 102 on its periphery, and a plurality of rolling cams 110, 111, 112 and 113.

When the cam means 100 is assembled on the rotor shaft 36, these rolling cams are uniformly spaced around the cam surface 102 and maintained in rolling contact therewith by being loosely held within slots 116 in a spider member 115. As shown in FIGURES 9 and 16, this

planetary cam assembly 100 in this embodiment is dimensioned for placement within a raceway defined between the interior of tubular portion 22 and the cam surface 102 of the cam sleeve 101.

To control the movement of latch 80, this planetary cam means 100 is mounted on the shaft 36 with the cam sleeve 101 spaced adjacent the latch and positioned so that the planetary rolling cam 110 is movable between the latch and cam sleeve along the cam surface 102 defined by the sleeve (FIGURES 9 and 16). Axial movement of the cam assembly 100 along shaft 36 is prevented by the adjustable nut 130 and washer 131 on the left, as viewed in FIGURE 9, and by the cam nut 120 on the right of the cam assembly. As shown in FIGURE 10, cam nut 120 is secured to shaft 36 by a suitable set screw 121, and may be finally adjusted during the assembly of the actuator mechanism in accordance with this invention by inserting the proper adjustment tool through the apertures 125 provided in the tubular portion 22 of the stator. The positioning of the planetary cam means 100 by means of adjustable nut 130 and the adjustable cam nut 120 in accordance with this invention thereby allows final adjustment of the relative positioning of the locking latch 80 and cam means 100 at the time of assembly, and eliminates the need for providing the bomb release mechanism with expensive parts machined to close tolerances.

The mounting of cam means 100 on shaft 36 in the above-described manner permits the planetary rolling cam 110 to be moved into a position to either lock or release the latch 80. In this first locking position of rolling cam 110, as seen in FIGURE 7, the engagement of cam 110 between latch 80 and cam sleeve 101 counteracts the above-described biasing force of spring 70 which tends to rotate the latch to its unlocked position, and releasably retains the latch locked against the plunger assembly 50. The underside of latch 80 preferably includes a recess 84 which assists in retaining the rolling cam 110 in this first position.

FIGURE 15 further illustrates the movement of rolling cam 110 along the cam sleeve 101 to a second unlocked position removed from engagement between latch 80 and the cam sleeve. With rolling cam 110 in this second position, the biasing force of the compressed spring 70 will quickly force the latch 80 toward the unlocked position shown in FIGURE 16 and thereby release the plunger assembly 50. Latch 80 is preferably provided with a bevelled edge portion 85, shown in FIGURES 7 and 15, which engages rolling cam 110 and facilitates the movement of the cam between the above-described first and second positions.

The movement of rolling cam 110 from the first position to the second position to release the latch 80 from the plunger 50 is selectively controlled by the rotation of the rotor shaft 36 induced by the energization of the solenoid 20. Projecting tongues 122 on cam nut 20 operably engage with corresponding grooves 117 in the cam spider 115 and transmit the rotation of shaft 36 to the rolling cams 110, 111, 112, and 113, as seen in FIGURES 10 and 11.

FIGURE 6 illustrates the engagement of tongues 122 in the grooves 117 with the bomb release actuator in a cocked energy storing position, and FIGURE 14 illustrates the position of tongues 122 within the grooves after the actuator has been released or fired. FIGURES 6 and 14 further show that the arcuate width of the grooves 117 in the spider 115 is substantially larger than the width of the corresponding tongues 122 so that the rotation of shaft 36 causes the tongues 122 to pre-travel through a predetermined arc before engaging with the spider 115 and actuating the release of the latch 80. This pre-travel feature of this embodiment of the invention, in which the tongues 122 pre-travel through approximately fifteen degrees, provides a lost-motion connection between the cam assembly 100 and the shaft 36 which permits the shaft to develop a substantial amount of

angular momentum before impacting the cam means 100 and assures a positive and quick release of the plunger assembly 50, as further described hereinafter. The degree of angular rotation of the cam spider 115 and the limit of travel of the rolling cam 110 in the cocked position is controlled by the engagement of a stop pin 86, extending from the latch 80, within groove 118 (FIGURE 10) provided in the periphery of the spider 115.

In operation, the bomb release actuator mechanism in accordance with this invention is initially retained in a cocked energy storing position, as illustrated in FIGURES 2 and 9, with the plunger assembly 50 releasably locked by the latch 80. In this cocked energy storing position, the solenoid 20 is deenergized, and the force of torsion spring 34 retains the rotor 35 in the position shown in FIGURE 3, with the stop pin 45 engaged against the shoulder 47. The pole pieces 37, 38, 39 and 40 of the rotor 35 are thus initially maintained in a spaced or gapped position with respect to the corresponding pole pieces 27, 28, 29 and 30 of the stator 21. This securing of the rotor 35 also prevents the rotation of rotor shaft 36 and cam nut 120.

During the assembly of the actuator, the cam nut 120 is adjusted to position the spider 115 of cam means 100 so that the rolling cam 110 is retained in the locking position engaged with latch 80, as shown in FIGURE 7, when the rotor 35 is in the above-described starting position. The proper initial positioning of spider 115 brings the spider into engagement with the pin 86 extending from the latch 80 into the spider groove 118, as shown in FIGURE 6. In addition, FIGURE 6 illustrates that the cam nut 120 is adjusted on shaft 36 so that the tongues 122 on the cam nut initially engage the spider 115 in an extreme clockwise position within grooves 117.

To release the plunger assembly 50 from this initial locked position, a low amperage energizing current is supplied to the coil 23 of solenoid 20 through the lead wires 25. This energization of solenoid 20 rotates the shaft 36 and cam nut 120 counter-clockwise by attracting the rotor poles 37, 38, 39 and 40 toward the stator poles 27, 28, 29 and 30 respectively with a magnetic force sufficient to overcome the clockwise biasing force of the torsion spring 34. After the rotor 35 and shaft 36 have travelled through approximately 35 degrees in this embodiment of the invention, the rotation of the rotor and shaft is arrested by engagement between the stop pin 45 and the tab 48', as illustrated in FIGURE 13.

As explained hereinabove, the cam nut 120 will pre-travel through an arc of approximately 15 degrees, and together with the rotor 35 will thus develop substantial angular momentum, before the tongues 122 on the cam nut impact against the counter-clockwise edge of the grooves 117 (FIGURE 14) and transfer the rotation of shaft 36 to the cam spider 115. The continued rotation of shaft 36 will then cause the spider 115 to force the rolling cam 110 from the locked position as shown in FIGURE 7 to a second or unlocked position, illustrated in FIGURE 15. The force of compressed spring 70, which urges the latch 80 downward as viewed in FIGURE 15, will assist in moving rolling cam 110 to this second position by the engagement of the cam with the bevelled surface 85, and will then quickly move the latch downward to its unlocked position disengaged from the plunger assembly 50. It is apparent from the above description that the movement of latch 80 to the unlocked position thereby releases the plunger assembly 50 from a cocked position, and permits the plunger to be driven outwardly from housing 10 into impact with a bomb shackle release-lever by the expansion of the compression spring 70. It is further apparent from the above description that the actuator in accordance with this invention requires less electrical energy to release, since the rolling contact between the rolling cam 110 and the latch 80 minimizes the frictional resistance of the assembly.

To recock the actuator for further use, the plunger

assembly 50 is forced inwardly, by any suitable means, until the spring 70 is compressed and the interior surface 83 on the plunger clears the detent 82 on the latch 80. The torsion spring 34, shown in FIGURE 13, will then rotate the shaft 36 and the interconnected rolling cam 110 clockwise, and cause the rolling cam to force the latch 80 up into the locked position against the plunger assembly. The actuator assembly in accordance with this invention is thus placed in an energy-storing condition, and may be released by selectively repeating the energization of the coil 20.

It will be appreciated that the foregoing description is merely illustrative of one embodiment of the energy storing and release mechanism in accordance with this invention. Various modifications of the aforementioned embodiment may be devised by those skilled in the art without departing from the scope of this invention, as set forth in the accompanying claims.

What is claimed is:

- 20 1. An energy storing and release mechanism comprising:
  - a housing defining an elongated chamber,
  - a plunger mounted within said chamber and longitudinally movable therein from an energy storing cocked position to a released position,
  - 25 energy storing means retained within said housing and operable to move said plunger from said cocked position to said released position,
  - 30 locking means supported within said housing adjacent said plunger, said locking means having a locked position in engagement with said plunger to releasably retain said plunger in said cocked position and further having an unlocked position disengaged from said plunger permitting said energy-storing means to move said plunger toward said released position,
  - 35 a shaft rotatably mounted within said chamber adjacent said plunger,
  - 40 planetary cam means positioned on said shaft and operable to releasably retain said locking means in said locked position, said cam means comprising a cam sleeve mounted on said shaft and defining an arcuate cam surface spaced adjacent said locking means and further comprising a planetary rolling cam engaged with said cam surface and movable thereon to a first position engageable between said cam surface and said locking means to releasably retain said locking means in said locked position, said planetary rolling cam being further movable on said cam surface to a second position permitting said locking means to move to said unlocked position,
  - 45 means to selectively rotate said shaft, and
  - 50 connecting means joining said planetary cam means to said shaft and operable to move said planetary rolling cam from said first position to said second position in response to rotation of said shaft and thereby permit said locking means to move to said unlocked position and release said plunger.
  - 55 2. An energy storing and release mechanism according to claim 1 wherein said connecting means between said shaft and said planetary cam means comprises a lost-motion connection permitting said shaft to pre-travel before transmitting rotation to said cam means, whereby said connecting means quickly moves said rolling cam from said first position to said second position with substantial angular momentum.
  - 60 3. An energy storing and release mechanism according to claim 1 wherein said means to selectively rotate said shaft comprises a solenoid supported in said housing adjacent said shaft and wherein said solenoid includes a rotor joined to said shaft and operative to rotate said shaft upon energization of said solenoid.
  - 65 4. An energy storing and release mechanism comprising:
    - a housing defining an elongated chamber,
    - a hollow plunger mounted within said chamber and

longitudinally movable therein from an energy storing cocked position to a released position, energy storing biasing means retained within said housing and operable to forcefully move said plunger from said cocked position to said released position, locking means movably supported adjacent the interior of said hollow plunger, said locking means having a locked position in engagement with an interior surface on said plunger to releasably retain said plunger in said cocked position and further having an unlocked position disengaged from said plunger permitting said biasing means to move said plunger toward said released position, a shaft rotatably mounted in said chamber and extending within said hollow plunger, planetary cam means positioned on said shaft within said hollow plunger and operable to releasably retain said locking means in said locked position, said cam means comprising a cam sleeve mounted on said shaft and defining an arcuate cam surface spaced adjacent said locking means and further comprising a planetary rolling cam engageable with said cam surface and movable thereon to a first position engaged between said cam surface and said locking means to releasably retain said locking means in said locked position engaged with said plunger, said planetary rolling cam being further movable on said cam surface to a second position permitting said locking means to move to said unlocked position, means to selectively rotate said shaft within said hollow plunger, and

connecting means joining said planetary cam means to said shaft and operable to move said rolling cam from said first position to said second position in response to rotation of said shaft and thereby permit said locking means to move to said unlocked position and release said plunger.

5. An energy-storing and release mechanism according to claim 4 wherein said connecting means comprises a cam nut fixed to said shaft and a cam spider movably mounted about said shaft in engagement with said rolling cam and wherein said cam nut and spider are connected by a tongue and groove connection so that said spider transmits the rotation of said cam nut to said rolling cam.

6. The invention according to claim 5 wherein said groove in said tongue and groove connection between said spider and cam nut is substantially larger than said tongue so that said shaft pre-travels and develops substantial angular momentum before transmitting rotation to said rolling cam.

7. An energy storing and release mechanism in accordance with claim 4 wherein said locking means comprises a latch pivotally mounted within said chamber and extending within said hollow plunger, said latch including a detent engageable with said plunger to releasably retain said plunger in said cocked position and further including a surface engageable with said rolling cam so that said rolling cam movably retains said detent of said latch in engagement with said plunger.

8. An energy storing and release mechanism according to claim 4 wherein said means to selectively rotate said shaft comprises a solenoid supported in said housing about said shaft and wherein said solenoid includes a rotor joined to said shaft and operative to rotate said shaft through a predetermined angle upon energization of said solenoid.

9. An energy storing and release mechanism comprising:

a housing defining an elongated chamber, a plunger mounted within said chamber and longitudinally movable therein from an energy storing cocked position to a released position, energy storing means retained within said housing and operable to move said plunger from said cocked position to said released position,

locking means supported within said housing adjacent said plunger, said locking means having a locked position in engagement with said plunger to releasably retain said plunger in said cocked position and further having an unlocked position disengaged from said plunger permitting said energy-storing means to move said plunger toward said released position, cam means cooperating with said locking means comprising a cam surface spaced adjacent said locking means and a rolling cam movable on said cam surface into a first position engaged between said cam surface and said locking means to releasably retain said locking means in said locked position, said rolling cam further movable on said cam surface to a second position permitting said locking means to move to said unlocked position, and

a solenoid supported in said housing adjacent said plunger including a rotor joined to said cam means, said rotor being operative upon energization of said solenoid to move said rolling cam from said first position toward said second position over said cam surface so that said cam means unlocks said locking means and permits said energy-storing means to forceably drive said plunger to said released position.

10. An energy-storing and release mechanism comprising:

a housing defining an elongated chamber, a plunger mounted within said chamber and longitudinally movable therein from an energy storing cocked position to a released position, energy-storing means retained within said housing and operable to move said plunger from said cocked position to said released position,

locking means supported within said housing adjacent said plunger, said locking means having a locked position in engagement with said plunger to releasably retain said plunger in said cocked position and further having an unlocked position disengaged from said plunger permitting said energy-storing means to move said plunger toward said released position, a shaft rotatably mounted within said chamber adjacent said plunger,

planetary cam means joined to said shaft and operably movable to a first position engaged with said locking means to releasably retain said locking means in said locked position, said planetary cam means being further movable to a second position permitting said locking means to move to said unlocked position,

means to selectively rotate said shaft, and connecting means joining said planetary cam means to said shaft and operable to move said cam means from said first position to said second position in response to rotation of said shaft and thereby permit said locking means to move to said unlocked position and release said plunger.

11. An energy-storing and release mechanism in accordance with claim 10 wherein said locking means includes a recess engageable with said cam means to resist movement of said cam means from said first position, and wherein said locking means further includes a bevel adjacent said recess to urge said cam means toward said second position as said cam means disengages from said recess.

12. An energy-storing and release mechanism according to claim 10 wherein said connecting means between said shaft and said planetary cam means comprises a lost-motion connection permitting said shaft to pre-travel before transmitting rotation to said cam means, whereby said connecting means quickly moves said cam means from said first position to said second position with substantial angular momentum.

13. An energy-storing and release mechanism in accordance with claim 10 wherein said locking means is pivotally supported at a position spaced from the point of engagement between said locking means and said

plunger so that said energy-storing means urging said plunger toward said released position operates through a lever-arm defined by said locking means to forceably urge said locking means toward said unlocked position, whereby said energy-storing means is operative to quickly move said locking means to said unlocked position in response to movement of said cam to said second position.
